UNITED STATES PATENT OFFICE.

FREDERICK A. HART, OF NEWARK, NEW JERSEY, ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,256,310.

Specification of Letters Patent. Patented Feb. 12, 1918.

Application filed October 6, 1913. Serial No. 793,575.

To all whom it may concern:

Be it known that I, FREDERICK A. HART, a citizen of the United States, residing in Newark, in the county of Essex and State 5 of New Jersey, have invented certain new and useful Improvements in Combined Type-Writing and Computing Machines, of which the following is a specification.

This invention relates to computing machines, and especially those in which numbers are printed in columns and in which a register may be appropriated to each column.

The invention is especially valuable in 15 connection with combined typewriting and computing machines, although it may be used in other kinds of machines.

In computing machines it has been customary to print on the work-sheet a distinguishing sign to indicate a clear or zero condition of the computing mechanism or to indicate some other particular fact in connection with some particular item, or in connection with such register as is active at 25 the moment; and in machines having a totalizer appropriated to each column, it has been customary to have a separate clearance printing key for each register operating its own clearance type. With such a construction it would be possible to print a clearance sign in any of the columns on the work-sheet without, in fact, having cleared the particular register appropriated to that column, thus giving a false assurance that the 35 totalizer in such column stood at zero. One of the main features of my invention, therefore, is the prevention of the printing of the clearance sign on the work-sheet at a column of figures which is being added in a 40 totalizer, which latter at the time was not standing at zero. Unless the totalizer, which is in use, stands at zero, the depression of the clearance key belonging to a different totalizer cannot cause the clearance sign to 45 be printed, even though said different totalizer may stand at zero.

In applying my invention to a combined typewriting and computing machine, the carriage is arranged to determine the column or columns in which adding or printing

is to be done, which carriage is also arranged to control the printing of the clearance sign in any particular column. In the construction shown the carriage is connected to a special key to determine in what column said key shall print the desired sign.

One form of key which is commonly used is one that prints a sign to show that the computing wheels all stand at zero. Such keys are commonly known as star keys or clearance-proving keys.

My invention is illustrated as applied to an Underwood-Hanson combined typewriting and computing machine, in which the typewriter carriage comprises the usual 65 platen about which a work-sheet may be passed, and is usually provided with denomination-selecting devices, or means for determining on what computing wheel the number represented by any numeral key operated shall be registered. Said carriage is sometimes provided with several denomination-selecting dogs, one for each register in the machine.

Where the special key in connection with 75 a register is the usual star key of said Underwood-Hanson combined typewriting and computing machine, the typewriter carriage may be provided with star-key-controlling or impression-controlling dogs corresponding to any or all of the aforementioned denomination-selecting dogs, each one of said impression-controlling or key-controlling dogs so coöperating with any star key that it permits said star key to be operated only at 85 the column or letter-space which is determined by said key-controlling dog.

In said Underwood-Hanson combined typewriting and computing machine, there is usually provided a star key for each register, each key operable only when its register stands at zero, all of said keys being connectible to a type bar to print a "star" in the column where computing is being done. According to my present invention, 90 there may be a plurality of impression-controlling or key-controlling dogs, each so set that it will be effective on only one, or selected ones, of the star printing keys or devices. Said key-controlling dogs may be 100

conveniently formed as tappets or lugs set along the ordinary column stop rack bar of the Underwood typewriting machine, and advantageously said lugs may be formed as extensions of the ordinary Underwood column stop. Said dogs may be located in different planes on said stops, and coöperate with correspondingly arranged cams, each cam controlling a predetermined star key or keys, but ineffective on any other star key or device. Said cams may be of a length corresponding to the width of column in which the printing is permissible. Where used for a key which should be operated only in a single letter-space in any column, said cams may be correspondingly formed to be effective over only such a letter-space.

This invention, it will also be noted, may be used to prevent the special character from being printed anywhere on the work-sheet except in proximity to the computing zone or zones.

Other features and advantages will hereinafter appear.

In the accompanying drawings,

Figure 1 is a sectional side view of so much of an Underwood-Hanson combined typewriting and computing machine as is convenient for showing my invention as applied thereto.

Fig. 2 is a diagrammatic plan view of the same with most of the parts broken away.

Fig. 3 shows the column stops and the key-controlling dogs thereon.

Fig. 4 is a skeleton perspective showing the connections between the tabulating rack bar, and the star key associated with one register.

Fig. 5 is a plan view of the star-key-controlling cams, showing one cam in effective position.

Fig. 6 is a rear view of the parts seen in Fig. 5.

Fig. 7 is a sectional side view of a register, its star key, and some of their connections.

In the usual combined Underwood-Hanson typewriting and computing machine, typewriter keys including numeral keys 1 when depressed swing type bars 2 upwardly and rearwardly against a platen 3, so as to cause type 4 on the type bars 2 to print on a work-sheet passed around said platen.

Said platen, as is usual, is mounted in a carriage 5, which carriage is fed along at every key stroke by an escapement wheel 6 with which the usual dogs 7 and 8 coöperate, said dogs being operated in the usual manner by a universal bar 9 which is moved by heels 10 on the type bars 2 at every key stroke.

Said typewriting machine also comprises the usual denominational tabulating keys

11 on key levers 12, said keys when depressed raising plungers 13 into the path of column stops 14, said column stops being mounted in the usual manner on a rack bar 15 forming part of the carriage 5.

Whenever a tabulating key 11 is depressed, it releases the typewriter carriage from the escapement wheel 6 in the usual manner not shown herein, so that the depression of said key automatically will cause the typewriter to come to rest by bringing the column stop 14 against a selected counter stop 16, which is formed at the upper end of the plunger 13.

As the typewriter carriage travels along, it causes the numbers represented by the 80 numeral keys depressed to be registered on the appropriate computation members 16^a, there being one of said computation members 16^a for each dial or computing wheel 17, from which computing wheels the added 85 numbers may be read by the operator through a sight opening 18.

To select the proper computation member 16^a, the typewriter carriage is provided with an upwardly extending bracket 19, 90 said bracket carrying a denomination-selecting dog 20, which, as the typewriter carriage passes along from left to right, raises *seriatim* a series of jacks 21, which are each connected to move a computation member 95 16^a to effective position, and when in said effective position, the numeral key 1 then being operated, will register on said computation member the digit represented by the key operated.

The connections for thus raising the computation members 16^a to effective position, include for each jack 21 a rod 22, which underlies the rear end of said jack so that as said jack is swung about its pivot 23 by 105 the denomination-selecting dog 20, the lower end of said jack will be moved downwardly to swing a lever 24 pivoted between its ends, causing the front end of said lever, through the usual Underwood-Hanson 110 transposition device 25, to raise the computation member 16^a corresponding to said jack into effective position. The transposition devices are shown more in detail in the British Patent No. 3390 of 1912.

Since the typewriter carriage travels to the left and the first digit must be registered on the left-hand computing wheel, said transposition device is necessary so that as said typewriter carriage moves from right to left, the digits will be successively registered in computation members beginning at the left and going toward the right.

The digits represented by the numeral keys struck, are registered *seriatim* on said computation members 16^a by settable pins 26, there being one pin for each digit. Between the numeral keys 1 and the computa-

tion members 16^a, are interposed pin-setting linkages 27, said linkages operable by rock arms 28 fast on shafts 29, each linkage being connected to one of said shafts, and 5 each shaft having a rock arm 30 fast thereon which is adapted to be struck by a pendant 31 hanging from the numeral key 1.

The connections are such that the descent of the pendant 31 with its numeral key 10 rocks the shaft 29 to swing its linkage 27 against the pin 26 which represents the digit on the numeral key operated, only one computation member 16^a at any moment having its pins 26 in effective position. 15 When all the digits representing the desired item have been thus set up on successive computation members 16^a by the depression of pins 26, said digits are carried into the computing wheels 17 by means of 20 a general operator, said operator including a cross bar 32 which comes forward and strikes the depressed pins 26, thereby carrying the computation members 16^a forwardly, so that racks 33 on the front ends of the 25 computation members will turn the computing wheels 17 through pinions and pawls not shown herein. It is evident that said movement of the general operator will, in the usual manner, rotate said computing wheels to an extent depending on the pins set up.

The general operator is operated in the usual manner by a handle, not shown herein, attached to the usual segment 34, which 35 segment, through an idle pinion 35, drives a rack bar 36 forming a side member of the general operator. The carrying over from one computing wheel to the next is done in the usual manner, not shown herein, on the 40 return stroke of the general operator. The computation members 16^a are brought back to normal position by said return stroke and the set pins are returned to normal position at the end of said return stroke.

45 Associated with each computing wheel 17 is a spring detent 37, which holds said computing wheel against improper turning. The computing mechanism also includes the usual star key 38, which when the computing 50 wheels all stand at zero, may be depressed manually to cause the "star" to be printed on the work-sheet on the platen 3.

The connections for accomplishing this printing may be of the usual kind, which 55 include a rock arm 39 fast on a rock shaft 39^a; said arm underlies the stem 40 of the star key 38, and is held up against said stem by a spring 41. Another arm 42 fast on said rock shaft 39^a carries a pin 43 riding 60 in a slot in a type-operating bell crank 44, said bell crank 44 operating one of the type bars 2 through a key lever 45 of the usual kind, except that it includes no key or key stem. The key lever 45, in place of

a key, has depending therefrom a link 46, 65 said link having at its lower end a stud 47, which stud underlies an arm 48 of the type-operating bell crank 44. The connections are such that when the star key 38 is depressed, it rocks the type-operating bell 70 crank 44 through the rock arm 39 to draw down the link 46 and swing the star key type-bar against the platen 3.

Said star key usually is arranged to be operable only when the computing wheels 75 17 all stand so they display their zeros through the sight opening 18.

According to my invention, the star key is normally held locked against operation by means of a locking spring associated 80 with each computing wheel; said locking springs, however, may be tensioned to make them ineffective when the computing wheels 17 all stand at zero. To bring about this result, the star key 38 may be normally 85 held locked against movement by an up-standing rock bar 49 which underlies the key proper near where the stem 40 enters said key.

Said rock bar 49 is fast on a rock shaft 90 50 mounted below the star key 38, and is under the constant tension of a comparatively weak spring 51, which, if the locking rock bar 49 is entirely unrestrained, will 95 swing said locking bar 49 to ineffective position clear of the star key 38. Said locking bar 49, however, is normally drawn to effective position under the star key 38 by any one of a number of comparatively strong locking springs 52, of which springs 100 there is one for every computing wheel.

The connections for causing said springs 52 to normally draw the locking bar 49 to effective position, include a bail 53 mounted on the locking bar 49 and on rock arms 54, 105 said bail forming a universal bar which draws the locking bar 49 to effective position under the star key 38, whenever any of the springs 52 are effective.

The connections between the springs 52 and said bail 53 include slotted links 55, whose slots engage the bail 53, and are of such length that the lost motion of the bail 53 in each slot is sufficient to provide for moving the locking bar 49 to effective or ineffective position. Said links 55, at their 110 rearward ends, are pivoted on upstanding pivoted tappets 56, said locking springs 52 normally drawing said tappets 56 rearwardly against the smooth periphery of the 115 computing wheels 17.

Each computing wheel is provided on its periphery with a cam 58 of sufficient height to strike a projection 57 on the tappet 56 and move the link 55 forwardly to such an extent that the slot in link 55 will permit the locking bar 49 to be moved to ineffective position, so far as the locking spring 52

associated with that computing wheel is concerned. The result of this is, that when all the computing wheels stand with their cams 58 opposite the points 57 of the tappets 56, the locking bar 49 will be free to be drawn to ineffective position by its weak spring 51, but if any one of the computing wheels fails to move its tappet 56 forwardly by its cam 58, its locking spring 52 will hold the locking bar 49 under the star key 38.

The combined machine, as herein illustrated, includes three registers shown diagrammatically in Fig. 2, and for each register there is a separate denomination dog 20, as shown at Fig. 1, said denomination dogs being placed in different vertical planes so that each denomination dog will coöperate only with one set of jacks 21, of which sets 20 the effective ends 59 lie in planes corresponding to the different denomination dogs 20. Each set of jacks has its own set of rods 22, its own transposition device 25, and its own set of computation members 16^a 25 and computing wheels 17, so that each set of computing wheels 17 forms a register separately operable in a manner determined by the typewriter carriage.

In these machines as heretofore constructed, there was usually a separate star key for each register, every star key operating its own type-operating rock arm 39, but since all said rock arms 39 were fast on the same rock shaft 39^a, the depression of any star key, if its totalizer stood at zero, might heretofore have caused the printing of a "star" in any of the other columns on the work-sheet, thus giving a false assurance that the totalizer in such other column stood at zero.

In order to prevent the operation of a star key 38 in any column except the column represented by the register then in use, means are provided for locking the star keys against operation at the wrong time. For this purpose, according to my invention, the stem 40 of each star key is cut off flat, and has normally held under it a locking rod or plate 60, as seen in Figs. 1 and 4. Said plate is normally held in effective position by a compression spring 61, and is guided by a recessed supporting plate 62, which hold it up against a plate 63 of the usual computing machine frame. The plate 60 is also provided with a pin 60^a riding in a slot 60^b to limit its motion.

Said locking plates 60 may be selectively moved to ineffective position whenever the typewriter carriage occupies predetermined positions, so that writing may be done in predetermined columns. For this purpose, according to my invention, the usual column stops 14 of the Underwood typewriting machine are provided with rearwardly extending dogs or lugs 64, each lug adapted to

strike and move rearwardly a cam 65 (see Figs. 1, 2 and 4), and each cam controls its own locking plate 60.

The connections between a cam 65 and its locking plate 60 include a vertical lever 66 pivoted between its ends in brackets 67 extending from the usual denominational tabulator casing, so that when the cam 65 is moved rearwardly, the lower end of the lever 66 moves forwardly, pushing a rod 68, said rod being attached to a lug 69 on the locking plates 60, said lug extending down below and between the plates 62 and forming, if desired, a guide for the locking plate 60.

From the above connections, it will be seen that if the typewriter carriage is positioned to compute in any given column by its column stop 14, said column stop at the same time will cause the cam 65 to move to ineffective position the locking plate 60, thereby releasing the star key 38, so that the operative may at any time depress said key if the computing wheels 17 in that column stand at zero.

In order to permit the star keys 38 of the separate registers to be selectively released, the various column stops 14 are provided with their lugs or tappets 64 set at various heights, and there are also provided corresponding cams 65 at various heights, each cam controlling a selected star key 38 by connections identical with those described above.

In the illustration shown herein, there are three registers, see Fig. 2, numbered "1," "2," and "3," beginning with the left-hand one. As the typewriter carriage travels along, it may be arrested by the denominational tabulating keys 11, so that its column stop 14 numbered "3" in Fig. 4, will first be operative to arrest the typewriter carriage. At this time, the denomination-selecting dog 20, "3," and its corresponding jacks, seen in the foreground in Fig. 1, are effective, and any numbers written in that column will be registered in register "3," Fig. 2. The star key 38 corresponding to that register, will at that time be freed from its locking plate 60 by the lug 64 of the column stop 14, by which the typewriter carriage has been arrested, said lug, as shown herein, being at the bottom of said column stop.

When a number has been registered at this point, the typewriter carriage may be similarly positioned by operation of a denominational key 11, to register in register "2," whose star key 38 will in the same manner be unlocked by the central lug 64 on the column stop 14. The register "2," in Fig. 4, has had its star key, not shown therein, unlocked by its unlocking rod 68. The cam 65, shown as effective in said Fig. 4, is the middle cam coöperating with the middle lug 64.

The typewriter carriage may again be positioned by a denominational tabulating key 11, and the column stop "1" will then be effective to arrest the typewriter carriage, 5 and its lug 64, at the top of said stop, will move said cam 65 to unlock the star key 38 of the register "1."

As best seen in Figs. 4 and 6, the cams 65, "1" and "2," are cut away at their rear 10 to allow levers 66 of the other cams to be at all times clear of the cams themselves. Said cams 65 themselves are rounded off at each end so that the camming lugs 64 will pass them readily when the typewriter carriage 15 moves in either direction. These cams 65 are joined to their levers 66 by triangular webs 69* which strengthen their backs. The levers 66 are held against twisting on their pivot 71 by broad sleeves 70 which are 20 interposed between said levers and brackets 67, on which brackets the pivot 71 is carried. The rods 68 which control the locking plate 60, are close together at their rear ends where they are joined to the levers 66 25 so that said levers may stand close together in a group. The rods 68, however, at the bottom of the machine, are bent outwardly, as seen in Fig. 4, and then forwardly, so that each rod, under its register, will move 30 in a nearly backward and forward direction.

While I have illustrated the cam 65 as extending over the full width of a column of denominational stops 11, it will be seen that this is done merely for the purposes of illustration, because said cams may be of any desired width to limit the number of letter-spaces over which any star key 38 may be operated. Said number of letter-spaces may be as small as a single letter-space, if desired.

I have not claimed broadly in this application matter disclosed in my pending application, No. 658,470, filed November 4, 1911.

Variations may be resorted to within the 45 scope of the invention, and portions of the improvements may be used without others.

Having thus described my invention, I claim:

1. In a combined typewriting and computing machine, the combination with numeral keys, computing wheels and a traveling carriage, of a plurality of registers into which said wheels are grouped, a special non-numeral key associated with said 55 wheels, a type under the control of said special key, and means controlled by said carriage for determining in what column said special key shall be effective on its type.

2. In a combined typewriting and computing machine, the combination with numeral keys, computing wheels, and a traveling carriage, of a plurality of registers into which said wheels are grouped, a key operable only when computing wheels stand at 65 zero, a type under the control of said zero-

controlled key, and means controlled by said carriage for determining in what column said special key shall be effective on its type.

3. In a combined typewriting and computing machine, the combination with numeral keys, computing wheels and a traveling carriage, of a plurality of registers into which said wheels are grouped, a special non-numeral key associated with each group, a single type under the control of all said special keys, and means for jointly controlling said special keys both by their respective groups of wheels, and by the carriage for determining in what column each special key shall be effective to control said type.

4. In a combined typewriting and computing machine, the combination with numeral keys, computing wheels and a traveling carriage, of a special non-numeral key 85 associated with said wheels, a type controlled by said special key, a member associated with each wheel for controlling said special key, and a member associated with the typewriter carriage and acting conjointly with said wheel control for controlling the column or position on the work sheet in which said special key causes printing.

5. In a combined typewriting and computing machine, the combination with numeral keys, computing wheels and a traveling carriage, of a plurality of registers into which said wheels are grouped, a special non-numeral key associated with each group 95 of computing devices of which said wheels 100 form a part, a single type selectively under the control of all of said special keys, and means under the control of the typewriter carriage for selectively determining which of said keys may be effective on said type. 105

6. In a combined typewriting and computing machine, the combination with numeral keys, computing wheels and a traveling carriage, of a plurality of registers into which said wheels are grouped, a zero-providing key associated with each group of wheels, a single type operable by any of said zero keys, a device on each computing wheel to control its zero key, and means under the control of the typewriter carriage and acting conjointly with said wheel control for selectively determining which of said keys may be effective on said type.

7. In a computing machine, the combination with numeral keys, a traveling carriage and computing wheels, of printing types, a special type operable to print a sign, registers comprising groups of said computing wheels, a key for each register controlling said special type, means on each wheel controlling its special type key, and means on the carriage acting conjointly with said wheel control for selectively controlling said special type key.

8. In a computing machine, the combina-

- tion with numeral keys and computing wheels, of a special printing key, a locking device for said special key, means associated with each wheel for normally holding said locking device effective, means on each computing wheel for disabling said effective means, and means for moving said locking device to effective position when every one of said effective means is disabled. 5
10. 9. In a computing machine, the combination with numeral keys and a gang of computing wheels, of a special printing key, a locking device for said key, means associated with each computing wheel for holding said locking device effective, means on each computing wheel for disabling said effective device, a universal bar under the control of every effective device of a gang, and a spring for making said lock effective when each 15 computing wheel is in disabling position.
10. In a computing machine, the combination with computing wheels forming a gang, of a lug on each computing wheel, a tappet for each lug arranged to be moved thereby 20 when its computing wheel stands at zero, a special printing key, a lock for said special key tending to become effective, and a spring for each tappet normally holding said lock effective but rendered ineffective by said lug. 25
30. 11. In a computing machine, the combination with computing wheels forming a gang, of a lug on each computing wheel, a tappet for each lug arranged to be moved thereby when its computing wheel stands at zero, a special key, a locking arm for said special key, a spring tending to move said locking arm to ineffective position, a bar connected to said locking arm universal to said tappets, and means associated with each tappet 35 for drawing said universal bar and lock to effective position against the tension of said spring.
12. In a computing machine, the combination with computing wheels forming a gang, of a lug on each computing wheel, a tappet for each lug arranged to be moved thereby 40 when its computing wheel stands at zero, a universal bar, a lost motion device connecting each tappet to said universal bar, a special key, a lock normally holding said special key but normally tending to move to ineffective position, and means associated with each tappet normally drawing said universal bar to hold said lock effective but moved 45 to ineffective position by said lug. 50
13. In a computing machine, the combination with a special key and a key stem, of two locks therefor, one of said locks comprising a bar movable under the key, and the other of said locks comprising a bar movable under the key stem. 55
14. In a computing machine, the combination with a traveling carriage and type printing *seriatim* thereon, of numeral keys, a plurality of registers controlled by said 60
- keys, a special key associated with each register, a single type under the control of all of said special keys, and means under the control of the carriage for determining which special key may be operated. 70
15. In a combined typewriting and computing machine, the combination with a traveling carriage and printing type, of numeral keys controlling said type, a tabulating stop settable on said carriage, a non-numeral key also controlling said type, and means associated with said stops for controlling said non-numeral key. 75
16. In a combined typewriting and computing machine, the combination with a traveling carriage and printing type, of numeral keys controlling said type, tabulating devices for positioning said carriage, a non-numeral key also controlling said type, and means associated with said tabulating devices for controlling said non-numeral key. 80
17. In a combined typewriting and computing machine, the combination with a traveling carriage and printing type, of numeral keys controlling said type, a non-numeral key also controlling said type, a tabulating stop rack bar on said carriage, and means settable on said rack bar for determining a letter space in which said non-numeral key will be effective to print. 90
18. In a combined typewriting and computing machine, the combination with a traveling carriage and printing type, of numeral keys controlling said type, a denomination selector carried by said carriage, a non-numeral key also controlling said type, a tabulating stop settable on said carriage to position said denomination selector, and means associated with said stop to control said keys. 95
19. In a combined typewriting and computing machine, the combination with a traveling carriage and printing type, of numeral keys controlling said type, computing wheels forming a totalizer, a non-numeral key associated with said totalizer, a printing type operable by said key, a column stop on said carriage, and means associated with said totalizer and said column stop for controlling said non-numeral key. 100
20. In a typewriting machine, the combination with keys and type operated thereby, of a traveling carriage, a plurality of special keys, a single type operated thereby, and means under the control of said carriage for determining which of said special keys may be effective on said single type. 105
21. In a typewriting machine, the combination with keys and type operated thereby, of a traveling carriage, a special key, a type operated thereby, and means under the control of said carriage for determining when said key may be effective on its type. 110
22. In a combined typewriting and computing machine, the combination with nu- 115
- 120
- 125
- 130

1. In a combined typewriting and computing machine, the combination with a plurality of gangs of computing wheels, a special key for each gang, a carriage, a plurality of tappets or lugs on said carriage, one for each of said keys, a plurality of cams, each individual to one of said tappets to be controlled exclusively thereby, a lock for each of said keys, and means connecting said cams to said locks, whereby when the carriage is in one position, one key is locked, and when the carriage is in another position, another key is locked. 70
2. In a combined typewriting and computing machine, the combination with a traveling typewriter carriage and a tabulating key therefor, of a column stop for arresting said carriage at a point determined by said keys, a gang of computing wheels, a special printing key associated with said gang, and means under the control of said column stop for locking said special key. 75
3. In a combined typewriting and computing machine, the combination with a traveling typewriter carriage and a tabulating key therefor, of column stops for arresting said carriage at a point determined by said keys, gangs of computing wheels, a special printing key associated with each gang, and means under the control of said column stops for locking any special key. 80
4. The combination of a gang of computing wheels, a special key, a lock for said key, a spring tending to release said lock, a series of stronger springs to prevent the lock from being released, and means to coöperate with said wheels to overcome such stronger springs and to permit the release of the lock by the first-mentioned spring. 85
5. The combination of a gang of computing wheels, a special key, a lock for said key, a spring tending to release said lock, a series of stronger springs to prevent the lock from being released, projections upon said wheels, and a series of devices operable by said projections to overcome the tension of said stronger springs and to permit the first-mentioned spring to release the lock. 90
6. The combination of a gang of computing wheels, a special key, a self-releasing lock for said key, a series of devices individually capable of holding said lock in effective position, and means to co-act with said wheels to force said devices to ineffective positions and permit the lock to release the key. 95
7. The combination with a carriage and a gang of computing wheels, of a device associated with said gang for printing a special character, two locks for said device, means for enabling said wheels to release one of said locks, and means for enabling said carriage to release the other of said locks. 100
8. The combination with a gang of computing wheels and a carriage, of a special key associated with said gang, a lock normally locking said key, a tappet or lug on said carriage, a cam operable by said tappet or lug, a lever connected to said cam, and a link connecting said lever to said lock. 105
9. The combination of a plurality of
10. gangs of computing wheels, a special key for each gang, a carriage, a plurality of tappets or lugs on said carriage, one for each of said keys, a plurality of cams, each individual to one of said tappets to be controlled exclusively thereby, a lock for each of said keys, and means connecting said cams to said locks, whereby when the carriage is in one position, one key is locked, and when the carriage is in another position, another key is locked. 110
11. A computing machine having printing mechanism, a carriage for determining the position of the columns to be printed on a work-sheet, adding mechanism for adding in different columns during the progress of said carriage; and comprising, in combination, a clearance sign printing type, and means adjustable along the carriage for rendering said type effective in different zones or columns. 115
12. A computing machine having computing devices and printing devices, for printing and computing in different zones; and comprising, in combination, a special clearance type, and means individual to the different zones to coöperate with said computing devices to control the printing of said special clearance type on the work-sheet in each zone. 120
13. A computing machine having printing means and computing means, to print and compute in zones or columns; and comprising, in combination, a clearance sign, a clearance key controlling the printing of said sign, and means to control the operation of said key to prevent it from printing outside of the zones to which belongs the clearance sign printed by the key. 125
14. The combination with a computing mechanism capable of computing in a plurality of different computing zones, of a special printing means for printing a characteristic mark indicative of a peculiar condition of the computing mechanism, and means individual to each zone for controlling said special printing means to enable the printing of a special indicating character in each computing zone when the computing mechanism corresponding to such zone is in a certain special condition. 130
15. The combination with a computing mechanism, of a carriage traveling to determine computing zones for said computing mechanism, a printing means for printing on a work-sheet carried by the carriage a sign characteristic of a certain condition of said computing mechanism, controlling means for governing the activity of said printing means, means for rendering said controlling means ineffective, and means for operating said controlling means from said carriage when said controlling means is ineffective condition. 135
16. The combination with a totalizer in-

- cluding a series of computing wheels, of a key, a lock for said key, means normally tending to release said lock, a plurality of restraining units for maintaining said lock in action, there being one of said restraining units for each of said computing wheels, and an enlargement on each of said computing wheels for positively releasing the associated one of said restraining units, whereby when 10 all of the computing wheels have the enlargements thereon in register and are in zero position, said lock will be automatically released to permit an actuation of said key.
37. The combination with a computing mechanism including a totalizer having a plurality of computing wheels, of a key, a lock for said key, a minor spring tending to release said lock, a plurality of major springs, one for each computing wheel, tending to 20 maintain said lock in action, and a series of units, one individual to each of said major springs, operated by said computing wheels to overcome the action of said major springs, whereby when all of said computing wheels 25 have assumed a predetermined relation said minor spring will be permitted to act to release said key.
38. The combination with a computing
- mechanism including a plurality of computing wheels, of a traveling carriage, and a key normally controlled by said computing wheels and said carriage jointly so as to be inactive but releasable when said carriage assumes a predetermined position at the same time that said wheels assume a predetermined relation.
39. The combination with a key, of a lock for said key, releasing means for said lock, a plurality of restraining units for said lock, each having a lost-motion connection with 40 said lock so that any number of said restraining units less than all can be in their releasing position while said lock remains in its active position, and a plurality of computing wheels, each having a change in contour thereof, for determining the releasing position of each unit, whereby when all of the changes of contour of said wheels are in register, and the wheels in a certain position, said lock will be silenced by said releasing 45 means, permitting an action of said key.
